UNITED STATES PATENT OFFICE.

FRANKLIN R. HOGEBOOM, OF BROOKLYN, NEW YORK.

COMBINED HORSE COLLAR AND HAME.

SPECIFICATION forming part of Letters Patent No. 308,966, dated December 9, 1884.

Application filed October 2, 1884. (No model.)

To all whom it may concern:

Be it known that I, FRANKLIN R. HOGEBOOM, a citizen of the United States, residing at Brooklyn, in the county of Kings and State 5 of New York, have invented certain new and useful Improvements in Combined Horse Collar and Hame, of which the following is a specification, reference being had therein to the accompanying drawings.

10 This invention relates to combined horse collars and hames, my object being to construct a collar and hame combined that will have a minimum weight, maximum strength, and which shall be composed of two swinging 15 sections so formed, joined, and limited in movement that all pressure shall be removed from the respiratory organs, and which shall conform its movements with those of the horse, thus preventing soreness, &c., caused by rubbing, as is the case when the ordinary collar 20 is used; and the invention consists in certain features of construction hereinafter described, and specifically pointed out in the claims.

Referring to the drawings, Figure 1 is a 25 plan, and Fig. 2 an end elevation partly in section, of a combined collar and hame constructed in accordance with my invention. Figs. 3 and 4 are details hereinafter described.

Like letters indicate like parts in all the 30 figures.

A represents a metallic plate having on its front surface the usual connecting devices for the traces, &c. Two of these plates are pivotally united to form a collar. Each of the 35 plates A not only acts as a foundation for the collar, but as a housing, preventing rain, &c., from injuring the collar, and also as a hame. The wither or top part of the plate is struck up to form any desired hinge-joint, A'. The 40 inner concave edges of the plates A are perforated, as at B, and struck up to form the small roll C, and the outer concave edges are in a like manner perforated. The rear side, D, is padded, as is usual, with hair or other material, and is covered by leather, the edges of which are united to the plates by stitches or otherwise passing through the perforations in the plate and through the leather. The lower 45 ends of the plates are cut away, as at E, struck up and bent over, as at F, thus forming one member of a hinge-joint. A link, bridge, or

connecting-piece G is pivotally secured to the plates by the pintles or pivots G', thus forming a hinge-joint. The link, bridge, or connecting-piece is cut away near each end, leaving a projecting lug or stop, G², against which the parts E of the plates come in contact when they are swung backward a certain distance as they partake separately and successively of the natural movements of the shoulders of the 55 horse. Outside of the parts E are the lugs G², the distance between which and the lug or stop G' is such as to allow sufficient play of the parts E between the lugs, necessary in the movement of the collar with the movement of 60 the shoulders of the horse. By this construction pressure upon the respiratory organs and chafing of the shoulders are prevented, and these advantages result in capabilities of drawing heavy loads and accelerating speed with 65 greater comfort.

It is readily apparent that each plate may be cut from suitable sheet metal, and struck up or formed in dies as well as perforated at its edges, whereby cheapness of manufacture and 70 lightness and strength in the completed article are secured.

To facilitate putting on or taking off the collar either of the bolts or pintles of the pivot or hinge-joints may be made removable; but 75 as the said bolts or pintles are arranged vertically to permit the independent swinging movement of each half of the collar a forward movement of both will, by reason of the projecting portions E, enlarge the opening between the two halves so that the collar will 80 pass over a horses head.

Having thus fully described my invention, what I claim is—

1. A horse collar and hame combined, the 85 upper ends of the leaves or halves of which are joined by a vertical pivot, and the lower ends of which are joined by vertical pivots located in forward extensions of said leaves or halves, whereby the collar may be enlarged 90 for putting the same upon a horse, substantially as specified.

2. In a horse-collar in which the ends are joined by vertical pivots, the forward extensions E F, in combination with the link G, 95 substantially as specified.

3. The metallic plates A, struck up, as at

C, and having the perforations B, with the link G, having the projections G¹ G², substantially as specified.

4. The plates A, struck up, as at F and E, to form hinge-joints, in combination with the bridge-piece G, having the raised portion G', and recessed portions G², substantially as and for the purpose set forth.

5. The sheet-metal plate A, curled on its concave side, as at C, and perforated at opposite edges, as B, and having the hinged members A' F, the latter formed on an extension, E, projecting from the body of the plate, substantially as shown and described.

6. The combined collar and hame comprising the plates A, each having a pad, D, secured by stitches at the perforated edges of the plates, the hinged connections A', F, and G, the latter having the stop G², substantially as shown and described. 15
20

In testimony whereof I affix my signature in presence of two witnesses.

FRANKLIN R. HOGEBOOM.
